UNITED STATES PATENT OFFICE.

JAMES W. JOHNSTON, OF SALT LAKE CITY, UTAH.

ELECTRIC IRON.

1,388,719.

Specification of Letters Patent. Patented Aug. 23, 1921.

Application filed April 5, 1920. Serial No. 371,409.

To all whom it may concern:

Be it known that I, JAMES W. JOHNSTON, a citizen of the United States, residing at Salt Lake City, in the county of Salt Lake and State of Utah, have invented new and useful Improvements in Electric Irons, of which the following is a specification.

This invention relates to electric irons or the like and comprehends the provision of means for holding the electric cord or conductor therefor sufficiently taut while the iron is in use, thus preventing the conductor from becoming twisted or becoming entangled with the clothes being ironed, or burning the user should the insulation of the conductor be broken and worn. While the invention is herein shown and described in connection with an electric iron it is to be understood that it is susceptible for use in other capacities or with other electric devices, and that its general application is contemplated by the claims.

The nature and advantages of the invention will be better understood when the following detail description is read in connection with the accompanying drawings, the invention residing in the construction, combination and arrangement of parts as claimed.

In the drawings forming part of this application, like numerals of reference indicate similar parts in the several views and wherein:

Figure 1 is a perspective view of an ironing board showing by full lines the normal position of the invention, and different adjusted positions, by dotted lines.

Fig. 2 is a detail sectional view, showing the connection between the support and the movable arm.

Referring to the drawings in detail, A indicates generally an ironing board which may be of any suitable construction, B an electric iron equipped with an electric cord or conductor C.

For the purpose above enumerated, I preferably make use of an arm indicated at 10 which may be constructed from any suitable material, size or cross sectional configuration, the arm being mounted upon the support or board A for universal movement. To this end, I preferably employ a coiled spring 11, the convolutions of which are closely related and attached to the board or support A and the arm 10. A sleeve or the like indicated at 12 is secured to the support

or board A by means of a fastening element 13 and a similar sleeve is secured to one end of the arm 10. Each sleeve is provided with annular grooves 14 which receive several convolutions of the adjacent extremity of the spring 11. By reason of this construction and arrangement of parts, it is obvious that the arm 10 is susceptible of being moved in any direction, and from a vertical position to an inclined position with respect to the board A as shown by dotted lines in Fig. 1. The arm supports an insulating sleeve 15 through which the conductor C is threaded, a second sleeve of insulating material being indicated at 16 and fitted upon the conductor C. The sleeve 16 is provided with a loop 17 to be engaged by the hook 18 carried by the arm 10 adjacent the upper end thereof. The sleeve 16 frictionally engages the conductor in a manner to prevent the latter from being drawn through the sleeve while the electric device is being used. Consequently the sleeve 16 can be positioned upon the conductor so as to maintain the latter taut between its point of connection with the sleeve 16 and the iron as shown in Fig. 1. When the parts are in normal position, the conductor is held taut between the iron and the point of connection with the sleeve 16, and yet when the iron is moved over the board A, the arm 10 is flexed to move with the iron and in this manner the conductor C is maintained tensioned. Consequently the conductor cannot become entangled with the clothes being ironed, or otherwise twisted which tends to break the insulation nor can the user be burned by having the conductor brought in contact with the arm or hand which would burn the user should the insulation be defective. The invention is simple in construction, and is designed to be readily and easily attached to any ironing board, or any other suitable support where it is found desirable.

While it is believed that from the foregoing description, the nature and advantages of the invention will be readily apparent, I desire to have it understood that what is herein shown is merely illustrative and that such changes may be resorted to when desired as fall within the scope of what is claimed.

Having thus described my invention what I claim as new is—

1. The combination with an electric device and its conductor, of a support, an arm

arranged above the support, a coiled spring providing a connection between the arm and support whereby the arm is mounted for universal movement, and means carried by the arm and associated with said conductor whereby the latter is held taut between its point of connection with the arm and said electric device.

2. The combination with an electric device and its conductor, of a support, an arm arranged above the support, a coiled spring providing a connection between the arm and

support whereby the arm is mounted for universal movement, a sleeve carried by the arm adjacent said spring to which said conductor is threaded, and an insulating sleeve projecting from the opposite sides of the arm adjacent the upper end thereof to which said conductor is threaded whereby the conductor is held taut between its point of connection with the arm and the electric device.

In testimony whereof I affix my signature.

JAMES W. JOHNSTON.
